(57) **CLAIM**

The ornamental design for a dispensing unit for distributing shaving tools, as shown and described.

DESCRIPTION

FIG. 1 is a perspective view of a dispensing unit for distributing shaving tools.

FIG. 2 is a front elevational view thereof.

FIG. 3 is a rear elevational view thereof.

FIG. 4 is a left side elevational view thereof, the right side elevational view being a mirror image of the left side view.

FIG. 5 is a top plan view of the dispensing unit for distributing shaving tools.

FIG. 6 is a bottom plan view thereof.
